IMPULSE TRANSMITTER

Julius Zuger, Oberageri, Lichtenberg, and Werner Koenig, Luzern, Switzerland, assignors to Landis & Gyr, A.-G., a corporation of Switzerland

Application December 21, 1937, Serial No. 180,952
In Switzerland December 24, 1936

1 Claim. (Cl. 177—380)

The invention relates to an improved method of and apparatus for selective remote control of operations of various kinds by means of interruptions of an alternating current network or supply circuit which feeds a receiver, such interruptions being effected by a transmitter. According to our novel method the selection of a definite operation is determined by the interval of time between two interruptions of the alternating current network or supply circuit (hereinafter referred to as the network). Our remote control method is useful for remote actuation or control of various kinds of operations, systems or devices, for example actuation or control of multiple tariff meters, of hot water storage plants, of street lighting networks, and the like.

The remote control apparatus designed for carrying the method into practice is preferably embodied so that on switching-in the network or supply, the selecting means provided at the transmitter and at the receivers are set in synchronous rotation, and that after a subsequent momentary interruption of the network the receiving selectors, corresponding to the time interval selected for a given operation or cycle between two interruptions, perform their operation and subsequently all the selectors come to rest upon reaching their initial position.

For the purpose of automatic remote control of the operations, a time element belonging to the transmitter can effect both the interruptions of the network and can also determine the duration of these interruptions. In such an arrangement the selector of the transmitter, running synchronously with the selectors of the receivers, starts the time element in operation and determines the length of time between two interruptions. Preferably there can be employed for the time element a contact selector with two groups of contacts, which are alternately connected to the corresponding contact arm of the selector. In this arrangement the contact arm is connected through the energizing winding of the time element to a network conductor A and through an operating contact of a relay, arranged in series with the contact arm of the contact selector, to a network conductor B; and one group of contacts is connected through the winding of a relay effecting the interruptions of the network to the network conductor A and the other group of contacts is connected through the energizing winding of the selector of the transmitter to the network conductor A, and through an off-normal contact of the selector of the transmitter and

the interrupter contact of the network to the network conductor B.

Furthermore for each operation to be remotely controlled a relay can be provided, which relay is energized by a circuit through depressing a push button switch provided therefor and through an interrupter contact of the network common to all the relays, and this connects the initial contact and the selector contact of the selector of the transmitter connected to the relay winding to the network conductor B through a stationary contact of a cut off relay. The cut off relay can be controlled by a contact closed by the selector of the transmitter shortly before its return to its initial position.

The method of our invention and a system and apparatus for practicing it, are diagrammatically illustrated in the accompanying drawing, wherein in the figure is a diagram showing the connections of a remote control system with automatic means for effecting the operations.

In general the transmitter comprises a driving mechanism, which is actuated from the network A, B connected to an A. C. source of electrical power and when set in operation makes a quite definite motion and runs at a constant speed. This mechanism further comprises a selector connected to and driven by this driving mechanism, and receivers E₁, E₂ and E₃ (of the type disclosed in the copending Koenig application, Serial Number 180,953 for Selective remote control, filed concurrently herewith, now Patent No. 2,203,358 of June 4, 1940) which are likewise actuated in an extension network A, B₁ by the transmitter connected with the network A, B.

The method of operation of the system of remote control is based on the fact that after an interruption of the network circuit the selectors are caused to run synchronously and at any desired time there is effected a momentary second interruption of the network circuit, after which receiving selectors set to this time effect their operation.

A remote control installation embodying the invention is exemplarily shown in detail in the diagram which illustrates a transmitter, capacitated for the automatic remote control of a variety of definite operations. In said exemplary embodiment, the transmitter connected to the network conductors A, B comprises a contact selector K₁, a synchronous motor S₁ connected to drive said contact selector; a time element K₂ formed as a contact selector having a rotatable arm c adapted to pass over and engage successively with series of contacts e₁ and e₂ of the

selector; and a synchronous motor S_2 connected to drive said time element. Associated with motor S_1 is an off-normal switch having its contacts f_1 and f_2 cyclically actuated thereby as fully disclosed in the Koenig application Serial Number 210,197, filed May 26, 1938, for Selective remote control apparatus, which issued at Patent No. 2,229,097, January 21, 1941, and diagrammatically indicated herein by a broken line actuator extending from motor S_1 diagonally upward to these contacts. There are also included contact relays V , W , X , Y , comprising correspondingly marked electro-magnets, connected to operate, respectively, the switches V_1 , W_1 , X_1 and Y_1 in the cross circuits connected as shown and operating as hereinafter described. (The magnets and their contacts are separated in the drawing but their inter-connections are indicated by broken lines.) A number of controlled contact relays Z_1 , Z_2 , Z_3 , corresponding in number to the definite operations to be performed or controlled by this exemplary layout are provided, and there are in circuit with said relays, respectively, push button switches D_1 , D_2 , D_3 corresponding to and adapted to open and close the circuits for the respective contact relays. Each of the contact relays Z_1 , Z_2 , Z_3 is provided with a working or actuating contact and with a holding contact, and these are correspondingly marked in sets a_1 , a_2 , a_3 , a_4 , etc. The relays Z and their push button switches are in parallel, and the circuit controlling, solenoid-operated switches Y_1 and X_1 are in series with them all. The receivers, E_1 , E_2 and E_3 are shown connected in the network A , B_1 , and represent the devices or mechanisms controlled by the precedingly described control means, these being taken exemplarily as three in number. The circuit connections will be clear from the diagram and their use and operation will be set forth in connection with the following description of the operation of the mechanism. It will be noted that the transmitters are connected to the network conductors A and B which are connected directly to the source of current, and that the receivers are connected to the network A and B_1 .

Operation of the foregoing is effected by selective operator actuation of one of the plurality of hand-operated contacts D_1 , etc., thereby energizing the corresponding receiver E_1 , etc. For example, if it is desired to energize receiver E_3 to control a given mechanism or function, the push button switch D_3 is closed and thereby a circuit A , a , D_3 , X_1 , Y_1 , B is closed, contact relay Z_3 is energized whereby working contact a_1 and holding contact a_2 of said contact relay Z_3 are brought to closed circuit positions. On releasing press button switch D_3 , contact relay Z_3 remains energized through a_2 , w_1 . When operating contact a_1 as described closed, a circuit A , V , b , a_1 , W_1 , B , is thereby closed, so that contact relay V is energized, its operating switch V_1 is closed and the energizing circuit of the synchronous motor S_2 is closed through V_1 and time-element contact selector K_2 is started. Also a circuit for interrupting relay Y is closed through V_1 , c , e_1 , and said relay Y thereby opens its switch Y_1 , whereby the first interruption of the network circuit A , B_1 is effected. The duration of this interruption is determined by the speed of the contact arm c of selector K_2 , which is being advanced by the synchronous motor S_2 and also by the breadth of the contacts of the contact group e_1 of said selector K_2 .

As soon as contact arm c of contact group e_1 75

comes on to contact group e_2 , the interrupting relay Y is de-energized and thereby network circuit A , B_1 is again closed, terminating said first interruption of this circuit. By the resting of contact arm c on contact group e_2 , two circuits are closed, of which one is formed through A , X , e_2 , c , V_1 , B and the other through A , S_1 , e_2 , c , V_1 , B . Relay X is thereby energized and its switch X_1 moved to open circuit position. By reason of the conditions thus established, the desired duration of the selected operation is safeguarded as the actuation of a further press button switch during the operation of the transmitter would be without effect. By the closure of the last-mentioned circuit synchronous motor S_1 is set in operation. Shortly after the response of the synchronous motor, the off-normal contact f_1 is closed. A circuit is thereby closed by way of conductor g being, the network conductor B through the switch Y_1 , conductor g_1 and through contact f_1 , to the synchronous motor S_1 and to the contact group e_2 . Contact arm c continues to be driven by synchronous motor S_2 , and on its engagement with the next contact of the group of contacts e_1 , there is a further advance movement of the synchronous motor S_1 due to the said circuit through conductor g .

Contact arm b of contact selector K_1 , driven by synchronous motor S_1 , after leaving the initial contact o effects an interruption of circuit A , V , b , a_1 , W_1 , B , and the de-energized relay V then interrupts its operating contact V_1 . Synchronous motor S_2 remains energized through circuit A , S_2 , c , e_2 , f_1 , g , y_1 , B , until contact arm c of contact selector K_2 engages with the next contact of contact group e_1 , when by the interruption of said circuit synchronous motor S_2 comes to rest. Contact arm c connected to the contact group e_1 then comes to rest. No energization of relay Y will occur as its circuit is held open by the switch V_1 . Only when contact arm b of contact selector K_1 , driven by synchronous motor S_1 , comes on to contact 3 , will circuit A , V , b , a_1 , W_1 , B for relay V be again closed, and the circuit thereby be closed at switch V_1 . This causes synchronous motor S_2 to again advance and also causes relay Y to be energized, and network circuit A , B_1 is then opened for the second time.

The interruption of the network circuit A , B_1 is terminated as soon as arm c of contact selector K_2 comes on to a contact of contact group e_2 . Arm b of contact selector K_1 will then also leave contact 3 , so that relay V is again de-energized and its switch V_1 is again opened. Synchronous motor S_2 continues to advance, as it is now fed through a circuit A , S_2 , c , e_2 , f_1 , g , Y_1 , B . It will however come to rest as soon as arm c of contact selector K_2 touches contact group e_1 .

Shortly before the initial position of arm b of contact selector K_1 is reached contact f_2 is connected to contact f_1 , whereby the cut-off relay W is energized and switch W_1 of cut-off relay W will then interrupt circuit A , a , a_2 , W_1 , B . Thus the winding a of relay Z_3 will be without current, and operating switch contact a_1 and holding switch contact a_2 of relay Z_3 will return to their initial positions. In the final position of contact selector K_1 , wherein contact arm b rests on the contact o , switch contacts f_1 and f_2 are opened, and the synchronous motor likewise comes to rest. The transmitter is thereby brought into the position ready for effecting another operation, which is initiated in like manner, i. e., by closing one of the push button switches D .

The invention in its broader aspects is not lim-

ited to the specific mechanisms shown and described but departures may be made therefrom within the scope of the accompanying claim without departing from the principles of the invention and without sacrificing its chief advantages.

What we claim is:

A transmitting arrangement for causing successive momentary interruptions in an alternating current power transmission line and for controlling the time interval between such interruptions, comprising a first synchronous motor energized from said line, a wiper arm driven thereby and a plurality of spaced contacts successively engageable by the wiper arm, a second synchronous motor energized from said line, a wiper arm driven thereby and a plurality of spaced contacts successively engageable by the second wiper arm, means whereby alternate contacts of the first plurality of contacts control the momentary interruption of the transmission line and the remainder control the energization of the second synchronous motor, a plurality of manually operated switches, each individual to a contact of the second plurality of contacts, means whereby

the second mentioned wiper normally engages one of the second plurality of contacts, means controlled by the operation of any one of the manual switches for energizing the first motor 5 provided the second wiper engages the normal contact, whereby said first motor moves the first wiper over its contacts to thereby first interrupt momentarily the transmission line and thereafter to close a start circuit for the second motor and the second motor then interrupts the circuit of the first motor at its normal position contact, means whereby a circuit for the second motor independent of the starting circuit is closed as long as the wiper arm is off its normal position, means controlled by each manual switch for rendering a corresponding contact of the second plurality of contacts effective to close a second circuit for the first motor and thereby cause another momentary interruption in the transmission circuit, the time interval between these interruptions depending upon the particular contact rendered effective by one of the manual switches.
